UNITED STATES PATENT OFFICE.

LLOYD T. REMICK, OF BROCKTON, MASSACHUSETTS, ASSIGNOR TO UNITED SHOE MACHINERY COMPANY, OF PATERSON, NEW JERSEY, A CORPORATION OF NEW JERSEY.

METHOD OF FINISHING EDGES.

1,226,117.

Specification of Letters Patent. Patented May 15, 1917.

Original application filed April 13, 1914, Serial No. 831,614. Divided and this application filed October 14, 1914. Serial No. 866,673.

To all whom it may concern:

Be it known that I, LLOYD T. REMICK, a citizen of the United States, residing at Brockton, in the county of Plymouth and State of Massachusetts, have invented certain Improvements in Methods of Finishing Edges, of which the following description, in connection with the accompanying drawings, is a specification, like reference characters on the drawings indicating like parts in the several figures.

This invention relates to the art of finishing the edges of sheet material, exemplary apparatus being shown whereby the steps of the method may be performed. By way of exemplification merely, the method is shown and described as applied to the treatment of shoe upper material such as leather or cloth, but it is to be understood that the invention is equally applicable to the treatment of other pliable sheet materials, particularly those of organic origin.

In the preparation of shoe uppers certain exposed edges, as, for example, those of the top of the upper and along the throat or fly, for example, either or both edges of a button fly, must be finished to present a smooth, attractive appearance. This is usually done by skiving the edge, applying cement thereto, and folding over the margin into position to be secured by the cement. The uppers may then, if desired, be stitched through the folded portion as a further securing means or for the purpose of ornamentation. This folding operation has been largely performed by hand, but is now, to a very large extent, very satisfactorily performed by machines of the type disclosed in application Serial No. 790,892, filed September 20, 1913, Glass. For performing certain steps of my improved method, an improved machine of the above type, which is covered by my application Serial No. 831,614 filed April 13, 1914, of which this application is a division, may be employed.

A general object of the present invention is to produce a finished edge which will not be liable to stretch, and to provide an edge for any purpose where additional strength along the margin of the sheet material to be finished is required. It has been found, for instance, that for certain classes of shoes, for example, Oxfords having uppers of rather firm leather, the usual fabric lining of the

upper may be dispensed with, provided the free margin of the upper at or adjacent to the portion which is subjected to the folding operation, above described, is suitably reinforced to prevent stretching. Any suitable form of reinforcing means may be used, as, for instance, a cotton or linen cord or tape which may, if preferred, be inserted in position to be covered by the folded over margin of the upper either before or in conjunction with the folding operation. For practical purposes it has been found that a cord introduced into the crease of the upper prior to the folding of the margin down upon the body portion of the work and extending in the crease entirely around the folded portion of the upper serves to provide the necessary firmness and strength usually secured by a fabric lining extending over the entire inner face of the shoe upper.

In a broad aspect the invention consists, therefore, in a method of reinforcing the edge of sheet material, and that method is shown by way of example as applied to shoe uppers, a reinforcing element such as a cord, thread, wire or other filament being applied along the folded margin thereof and held in place by suitable cement. The upper may be lined or unlined, and, preferably, the margin of the upper is skived prior to the folding operation in order to form a neat and attractive fold, the folded portion being hammered down flat and secured by the cement.

In working upon shoe uppers and upon similar work, as bags, pocket books and the like, many corners having curves of a short radius, both concave and convex, have to be gone around. In order to secure a smoothly folded edge about such curves, especially the concave curves, it is necessary to slit the margin of the upper in conjunction with the application of the reinforcing element, and accordingly an important step of my improved method comprises the slitting of the margin to relieve the strain which would otherwise result and to form a smooth edge contour at the fold. This slitting operation may conveniently be performed in conjunction with the application of the reinforcing element, and, preferably, is done prior to the application along the fold of the said element.

Another feature of my improved method

consists in introducing into the fold formed by said mechanism the reinforcing element, the operations of folding the upper and introducing the cord taking place progressively and, preferably, substantially simultaneously. Preferably, too, and as a feature of the invention, the method comprises the pressing of the folded margin of the upper upon the body of the work and upon the 10 cord. The invention also contemplates the feeding of the cord with the work. Furthermore, as the cord is fed, the portions of the cord to be fed are drawn into the fold and included therein as the folding operation progresses. It is important that the reinforcing element or cord be introduced directly into the fold at the point of formation of the fold so that work, the edges of which are very sharply convex or concave, 15 may be handled. This feature of the invention is particularly valuable when operating upon shoe uppers which necessarily have sharp curves which must be gone around in the operation of folding the upper and into 20 the bight of which folds the reinforcing element should be introduced. When the point of introduction of the cord is close to the axis about which the work is turned in going around curves, whether convex or concave or whether the curve is one of large or small radius, the cord will be introduced 25 into the vertex of the fold.

To secure the material in folded position the margin of the material is given a coating 30 of cement which holds the contacting faces firmly together after the formation of the fold and the pressing together of the folded portions. In accordance with an important feature of the invention the cord is so introduced into the fold that the cord engages the cemented portion of the upper and accordingly when the fold is complete the cord is cemented to the upper and is permanently 35 and securely held in position.

Furthermore, as pressure is applied to the fold in order to cause firm adherence of the cement, a greater pressure is exerted on those portions between which the cord is held by reason of the greater thickness of the material at this point, and, hence, the adherence 50 of the cement along the cord and adjacent parts is particularly strong.

It is to be understood that the reinforcing member referred to above as a cord or reinforcing element may be variously located and may be a thread, tape, band, string or other suitable element, which, for the purposes of this application, may be termed a filament or filamentous element. It is, however, preferable in the case of shoe uppers to employ a filament of organic origin, as a cord or tape of cotton or linen.

These and other features of the invention will be described in connection with an illustrative apparatus, by which an exemplary

method may be carried out, and will be pointed out in the appended claims.

Referring to the accompanying drawings:

Figure 1 is a perspective view of folding and cord introducing instrumentalities 70 which may be used in the practice of my method;

Fig. 2 is a similar view to Fig. 1 showing the apparatus in the act of performing certain steps of the method;

Fig. 3 is a detail of part of the apparatus to be described;

Fig. 4 shows the step of cementing the margin of the material; and

Fig. 5 is a view of a shoe upper upon 80 which the improved method has been practised.

Exemplary instrumentalities by which this invention may be practised are shown in Fig. 1. They comprise a work table 2 and an overhanging arm 4 upon which certain of the operating instrumentalities are mounted, all of which will be presently described.

It will be understood that in carrying out my improved method upon a shoe upper the margin of the upper is first skived and that cement is then applied to the margin of the upper in any suitable manner; for example, by a brush 6 as shown in Fig. 4 of the drawings. To initiate the operation of folding 95 the margin of the material the work is presented to the machine and the edge is pushed back into engagement with the upwardly curved surface of a plow 10 whereby the edge is turned upwardly until it encounters an overhanging arm 11 of the plow or until it engages the pivot gage 12 which may be adjusted somewhat below the projection 11. The portion 11 of the plow 10 or the pivot gage 12 determines the distance 100 the material can be inserted, and, hence, determines the width of the fold. The gage 12 may be adjusted by a screw 14 to vary to some degree the width of the fold. If a greater variation in the width of the fold 110 than can be secured by an adjustment of the pivoted gage 12 is desired, the plow 10 may be removed and one of a different shape inserted in its place.

During the formation of the fold in the 115 margin of the sheet the work is clamped by the yielding presser 20 which is actuated upwardly at the proper time to press the work against the under face by a co-operating member, here shown as a creaser 120 22. The presser 20 is actuated through resilient means to avoid excessive pressure on the work and to permit its retraction manually for the introduction and removal of the work. The line of fold in the upper is determined by the lower edge of the creaser 22 which co-operates with the folding finger 24 which is actuated upwardly and at an inclination toward the front of the machine to fold the margin of the upper 125 130

across the lower edge of the rear face of the creaser 22, and to give to that edge a total bend of more than 90° relatively to the plane of the body of the sheet. The 5 upward movement of the folding finger 24 to form this fold or loop in the stock is performed while the stock is clamped between the face of the creaser 22 and the presser 20. At this stage in the treatment 10 of the material, and in accordance with the present invention, a reinforcing member is applied to the work and, preferably, may be inserted into the fold which is being made in the manner described. The reinforcing member 30 which, for convenience 15 may be referred to as a cord, is brought from a spool or reel, not shown, through a hole 32 formed in the creaser member 22, the fold being inclined rearwardly and toward 20 the left. The fold is also inclined downwardly and emerges on the rear face of the creaser, preferably, however not necessarily, at a point a short distance from the left hand end of the creaser, which is its advance end, with relation to the direction 25 of feed. From the hole 32 to the advance end of the creaser a groove 34 is formed which serves as convenient means for guiding the reinforcing element and locating it 30 in the bight of the fold formed by the folding mechanism. The groove 34 insures that the cord will be properly placed in the angle formed in the upper and serves particularly to position it accurately in the 35 bight of the fold. This groove, however, may be in either of the acting faces of the creaser. The groove 34 being shallow and located as near as possible to the lower edge of the rear face of the creaser, the 40 reinforcing member is introduced into the bight of the fold and directly against the inner face of the upper material. Preferably, a suitable tensioning device 36 is provided which is mounted upon a bracket 38 45 secured to the head of the machine at 40. The cord is guided from the reel or spool through the tensioning device 36 to the opening 32 in the creaser 22, through which it is threaded.

50 When a concave or inside curve of the material is being folded it is desirable at this stage in the folding operation to snip the marginal portion of the edge. For performing this step in the method, a snipping knife 50 may be employed. The knife 50 is mounted on a lever 52 pivoted to the arm 4 at 54 and operated by a connection 56 and actuating means located below the table 2. The knife 50 co-operates with the 60 advance edge 58, Fig. 1, of the plow 10 to make a shearing cut through the marginal portion of the material, which cut enables the fold to be properly formed around a concave curve of the material being 65 treated, as shown at *a* in Fig. 5. For

straight edges the use of the snipping knife is usually discontinued.

After the cord has been inserted, and, when necessary, the upper snipped, the margin of the sheet material must be folded down upon 70 the body portion thereof and the parts pressed firmly together to effect the setting of the cement, and then the work must be fed along to present a new portion of the material to the folding instrumentalities. 75 For this purpose there are provided the anvil block 70 and the hammer 72. To prevent undue stretching of the edge of the work between the rearmost portion of the margin being treated which is bent up by 80 the folding finger 24 and the advance portion which is folded over upon the body of the work, the work is held in an oblique position instead of being folded flat in the plane of the body portion of the work. 85 The work supporting surface of the anvil block 70 is beveled obliquely downwardly toward the yielding presser 20; that is, toward the point where the fold is completed, and also toward the rear of the 90 machine; that is, toward the line of direction of the feed of the work. This oblique position of the work is of advantage also where a convex portion of the work is being treated since it facilitates the formation of 95 the transverse creases or plaits which are necessary to take care of the fullness of the edge; these are shown at *b* in Fig. 5.

It is important that the means for completing the fold and pressing the folded portion upon the upper portion, comprising the anvil 70 and hammer 72, be located contiguous to the presser 20. The hammer 72, therefore, is actuated forwardly and downwardly to fold over a portion of the 100 margin of the material and press it firmly against the anvil in such a manner that the point of completion of the fold will be at the forward edge of the anvil block. This operation should be effected without 105 bending the margin of the work to a sharp angle and, therefore, the advance edge of the creaser 22 is cut away at 74 to give space for the upper material, and yet permit the hammer 72 to approach very closely the 110 advance edge of the creaser. The performance of the folding operations in a short space longitudinally of the direction of the feed is effected by the above described instrumentalities, and insures great facility 115 in going around sharp curves which frequently occur in work upon shoe uppers.

After the fold has been firmly pressed between the hammer and anvil the work must be advanced to present a new portion 120 of the work to the folding instrumentalities. This may be conveniently effected by moving the anvil and hammer, while they still grip the work in the direction in which the work is to be fed. Since it is practicable to 125

employ a longer feed movement when folding a straight edge than when folding a curved edge, the length of the feed movement is preferably under the control of the operator, and may be varied during the folding operations to suit the portion of the work being treated.

In order to insure that the feed of the work shall take place when the stock is first presented to the folding instrumentalities without the operator's taking care to advance the work far enough to be seized between the anvil and hammer, a foot 76 is provided. The foot 76 may be of resilient material and may be secured to the hammer 72, and extend forwardly into a space formed by cutting away a portion of the creasing member 22 in which space the stock will be exposed when first inserted under the creaser. The front end of the foot 76 is down-turned at 80, Fig. 1, to form a toe which gets a firm grip on the material and insures a positive feed of the work as the hammer moves to the left in the direction of feed.

In the practice of my improved method the upper material is prepared as indicated in Fig. 4 by applying a coating of cement to the marginal portion of the stock which is to be folded. The cement may extend over both faces of the material which are brought together in the folding operation or may be applied to either one of these faces only, and the stock may be either skived or unskived. Preferably, the portion of the material with which the cord is to come in contact is cemented so that the cord will be held to the material, and when the cord is located in the angle of the fold, will be permanently located whether or not the folded margin is further secured by stitches. The folding is then begun at a convenient point upon the margin, the creasing point or line being determined as by the edge of the creaser 22, and the reinforcing element is applied to the cemented margin or inserted in the crease as by the groove 34. In treating curved edges, especially concave or inside curves, it is important at this point in the operation to slit the margin of the material so that a smooth edge will be obtained, which will have no tendency to curve or pucker. The fold is then carried farther as by the action of the folding finger 24 to inclose the reinforcing element in the angle formed by the material, and the fold is then completed by pressing the marginal portion down upon the body portion, preferably while the portions so pressed together are maintained at an angle to the edge being folded, and also, preferably, at an angle transverse to that direction, this operation being effected, as shown by the hammer 72 and the anvil 70. This angular position of the work re-

sults in the release of the strain on the material which is in the act of being formed into a fold, and also facilitates the formation of a smooth edge upon a sharply convex or outside curve in the formation of which the excessive fullness of the edge is disposed of by pressing the folded portions while held in said inclined position.

It will be understood that when the above described instrumentalities are employed, the operations of folding the successive portions of the upper and inclosing the reinforcing element, will proceed automatically and that when one piece of work is finished another may be inserted without cutting the cord, the cord being severed between the pieces when a run of work has been completed.

It is convenient also to perform the slitting operation upon the upper while it is turned up in its vertical position and before it is pressed down upon the inclosed cord, the upper being then in the plane above the plane in which the cord is introduced, whereby all danger of interference between the cord and slitting means is avoided.

Having thus described my invention, what I claim as new and desire to secure by Letters Patent of the United States is:

1. That improvement in the method of finishing the edges of sheet material which consists in moving the material intermittently, forming step-by-step in the margin of the material during its periods of rest a fold, applying during each intermittent movement a portion of a reinforcing element in predetermined relation to said fold and intermittently securing to the body of the material said folded over margin and said portion.

2. That improvement in method of finishing an edge of sheet material which consists in cementing the marginal portion of the sheet, thereafter progressively folding over the cemented margin of the sheet, progressively applying in predetermined relation to the folded portion a reinforcing element, and progressively securing the folded portion and the reinforcing element to the body portion of the sheet.

3. That improvement in method of finishing the skived edge of a sheet of material which consists in applying cement to the skived portion, forming a crease or angle in the skived portion, laying a reinforcing member in said crease, folding the skived portion over against the body portion of the sheet, and pressing the folded portion and the reinforcing element against the body portion of the sheet.

4. That improvement in method of finishing an edge of sheet material which consists in applying cement to the inner side of the marginal portion of the material, thereafter initiating a fold in said cemented

portion, introducing a reinforcing element into the fold, and completing the fold to inclose the reinforcing element in the fold and to bring the cemented surfaces of the 5 fold and the reinforcing element into holding relation to the sheet material.

5. That improvement in method of finishing the edges of sheet material which consists in forming step by step a crease or angle in the marginal portion of the material, 10 laying a reinforcing element progressively into said crease or angle, slitting the margin of the upper, folding the margin of the upper over said element and down upon the 15 body portion of the material, and securing the folded portion and the body portion together.

6. That improvement in method of finishing the edges of sheet material of organic 20 origin which consists in applying cement to the inner side of the marginal portion of the material, initiating a fold in said portion, slitting the margin of the initiated fold, introducing a reinforcing element into the 25 fold, and completing the fold to inclose the reinforcing element in the fold and bring the cemented surfaces of the fold and the reinforcing element into holding relation to the sheet material.

30 7. That improvement in method of finishing the edges of sheet material which consists in treating successive portions of the margin thereof by turning up a portion of said margin to form a crease, laying into 35 the crease a reinforcing element, slitting the edge of the upturned portion, completing the folding of said portion by pressing it down upon the body portion of the material, feeding the material by progressive 40 movement of the portion last treated, and repeating the operation progressively about a substantial portion of the margin of the sheet.

45 8. That improvement in method of finishing the edge of sheet material which consists in applying cement to the margin of the material, initiating a fold in a portion of said margin, introducing a reinforcing filament into the initiated fold, completing the 50 fold to inclose the filament in the fold, feeding the work while initiating the fold in a succeeding portion of the margin and maintaining the plane of the completed fold at an inclination toward the plane of the 55 succeeding portion of stock in which the fold has been initiated to relieve strain upon the edge of the portions of the margin held at different inclinations, and repeating the operation progressively upon successive 60 portions of the margin of the material.

9. That improvement in method of finish-

ing the curved edges of sheet material which consists in treating successive portions of the margin by turning up said portions to a position at an angle to the body of the material, inserting a reinforcing filament into the angle so formed, completing the folding of said portion to inclose the reinforcing filament while maintaining the folded portion at an angle to the direction of the crease 65 formed in a subsequent portion, feeding the work by movement of the fold-completing means while at the same time initiating a fold in a subsequent portion, and repeating the operation progressively around the 70 75 curved margin of the material.

10. That improvement in method of preparing shoe uppers which consists in treating successive portions of the margin of a shoe upper by turning up a portion of said 80 margin to form a crease therein, laying into said crease a reinforcing element, completing the folding of said portion by hammering it down upon the body portion of the upper, and repeating the operation 85 progressively about a substantial portion of the margin of the upper.

11. That improvement in method of finishing the edges of sheet material which consists in applying cement to the marginal portion of the sheet, forming a crease or angle in the marginal portion, laying a reinforcing member along the margin of the sheet in predetermined relation to the crease, folding the marginal portion over against 95 the body portion of the sheet, and pressing the reinforcing member against the body portion of the sheet with a pressure in excess of that with which the marginal portion of the sheet is pressed against the body 100 portion of the sheet.

12. That improvement in method of finishing the edges of sheet material which consists in applying cement to the inner side of the marginal portion of the material, initiating a fold in said portion, introducing a reinforcing element into the fold, completing the fold and inclosing the reinforcing element in the fold, applying pressure to the marginal portion to force it 110 against the body portion of the sheet, and applying greater pressure to the reinforcing element to force it against the body portion of the sheet.

In testimony whereof I have signed my name to this specification in the presence of two subscribing witnesses.
